UNITED STATES PATENT OFFICE

1,941,930

METHOD AND MEANS FOR REPLACING
RAILROAD RAILS

Pierre Collet and René Loiseau, Paris, France;
said Collet assignor to Les Fils D'Albert Collet,
Paris, France, a company of France

Application July 15, 1932, Serial No. 622,792, and
in France July 18, 1931

3 Claims. (Cl. 104—5)

In the maintenance of the road beds of rail-ways, it is often necessary to replace the rails, either because they are worn or because the in-crease in traffic requires a larger cross-section, 5 or for other reasons.

Before our invention the replacement has been effected as follows: The new rails are stacked, and after removal of the old rails the new rails are laid in place, the positioning being performed 10 either by hand or by means of handling devices running over the still existing portions of the old track. When the cross-section of the rail is be- 15 ing changed, the rail seats in the ties are readzed by hand or by means of a mechanical device.

Such operation is lengthy and toilsome and re-quires considerable skilled labor, chiefly for re-adzing the seats.

The method according to our invention re-moves these drawbacks and provides a very ma- 20 terial economy in labor, at the same time re-quiring no skilled workman.

It consists primarily in using the new rails required for replacement, for first laying a service track parallel to the track which is to be replaced. 25 This service track serves for performing all the operations required in the changing of rails: to wit the removal of the old rails, the readzing of the ties, the boring of holes in the ties, the im-pregnation of the seats, and the handling of the ma- 30 terial in the yard, after which the service rails are slipped in place of the removed rails and over the old ties so as to form the new track.

In the form of our invention, which is preferred we use traveling jacks extending over the service 35 track for transporting the rails which have been removed, on to low flat cars running on the old track, the flat cars being then caused to move on while the jacks which are left in place enable the removal of a further length of the old track 40 rails thus uncovered, thus making the replace-ment a continuous operation.

Our invention also has for its object the pro-duction of new apparatus for carrying out our 45 novel method.

Our invention will be more readily understood from the following description given by way of example and corresponding to the appended drawings.

Figs. 1, 2, 3, 4 and 1a, 2a, 3a and 4a show dia- 50 grammatically both in side and in plan views the different phases in the execution of our method.

Fig. 5 is an end view of a flat car and a travel-ling jack used for the replacement operation.

Fig. 6 is an end view of a car adapted to run 55 both on the service track and on the old track.

Fig. 7 is a side view of the tie brushing device.

Figs. 8 and 9 are similar views of the tie re-adzing device and a modification thereof.

Fig. 10 shows in a similar manner the tie bor- 60 ing device.

Figs. 11 and 12 are side and end views of the tie impregnating device.

Figs. 13 and 14 are side and end views of an auxilliary system aiding in handling the rails.

We will first describe in detail with reference 65 to Figs. 1, 2, 3 and 4 and 1a, 2a, 3a and 4a the succession of operations according to one man-ner of executing our invention.

Fig. 1 shows a train such as may be used for 70 replacing the rails over a certain track length. This train comprises a work car 1, a certain num-ber of low flat cars 2, 3, two in the example shown, each provided each with three trucks and carry-ing the new rails intended for replacement, empty 75 cars 4, and cars 5 similar to cars 4 and carrying the material required for replacement and opera-tion.

Fig. 2 shows the rails unloaded from their 80 flat cars and disposed on either side of the old track 7 so as to form a service track 8. To this end the new rails are alined and connected to-gether so as to form two continuous lines run-ning parallel with the old rails and suitably spaced apart, say about 2.30 meters. In the case of the usual track the gauge is 1,435 meters.

Fig. 3 illustrates the removal of the rails of the 85 old track 7 between the rails of the service track 8. After dividing the train, the work car 1 and the flat cars 2, 3 advance leaving behind them the cars 4 and 5 on a part of the old track alongside of which no service track has been laid.

In the part of the track located between the 90 flat cars 2, 3 and the cars 4, 5, the rails to be re-placed are freed from their securing means. Travelling jacks 9 are then set on the service track for raising the rails and these jacks carry-ing the removed rails are carried along the service 95 rails over the flat cars 2, 3 on which they deposit the rails, so that the flat cars are loaded with the old rails.

The empty cars 4 (Fig. 4) are then brought to 100 the front of the removed part of the old track 7. To this end, the cars are provided with means for running on both the old track and on the service track. Between the empty cars 4 and the 105 cars 5 out of which we remove the desired mate-rial, may be arranged a miniature yard with de-vices adapted to run over the service track. These devices comprise for instance a tie brushing de-vice 11, a device 12 for readzng the ties, a device 110

13 for boring them and a device 14 for spraying a preservative on these ties, it being assumed in the cited case that the old rails are to be replaced by new rails having a different cross-section and 5 that it is necessary to readze the ties.

It will be noticed that after the travelling jacks have unloaded their used rails on the flat cars 2 and 3, they are in a suitable position for the further removal of the old track, after the flat cars 10 have been advanced. The operation thus may be a continuous one.

Once these different operations are at an end, the rail securing material such as coach screws, spikes, chairs, saddles and the like contained in 15 the cars 5 are distributed along the service track 8. It is then sufficient to slip the service rails 8 on the ties in the place which was previously occupied by the removed rails and to secure them in the place prepared for them.

20 We will now describe with more detail the different apparatuses which may be used to advantage for executing our invention.

Fig. 5 shows in front view a three-truck flat car for transporting the new and the old rails, together with one of the travelling jacks serving 25 for the removal of these rails from the old track on to the flat cars. The latter are comparatively low cars of the ordinary type comprising pairs of wheels 16 interconnected through rigid bars with 30 a gauge or spacing such that they can run over the old track 7. The travelling jacks each comprise a rigid bar 19 resting on pairs of wheels 21, the gauge or spacing of which is such that they can run over the service track 8. Jacks 22 controlled 35 through the hand wheels 23 permit adjusting the bar 19 into horizontal position when the rails 8 of the service track are not at the same height, for instance at curves where one of the rails is elevated above the other. The hoisting 40 device 24 may run along the bar 19. The handwheel 25 of this device controls the cable 26 and the pincers 27 whereby it is possible to lower a rail such as 28 on to the flat car.

Fig. 6 shows one of the cars (such as those 45 designated as 4 and 5 on Figs. 1 to 4) which may run both on the old track and on the service track. These cars comprise a box such as 29, and their wheel pairs 31 have a gauge or spacing corresponding to normal gauge and are connected 50 through rigid bars 32 both with each other and with pairs of wheels 33, the spacing of which corresponds to the gauge of the service track. The pairs of wheels 33 are connected with the bar 32 through the jacks 34 actuated by the 55 handwheels 35. These jacks when required, bodily raise the normal wheels 31, together with the bar 32.

Fig. 7 shows the apparatus for brushing the ties after removal of the old track. This brushing device is carried by the pairs of wheels or 60 rollers 36 spaced in accordance to the gauge of the service track 8. It comprises a mechanical, electrical or other pneumatic suitable motor 37 which drives, through a suitable transmission, 65 very hard rotary brushes 38 which brush the part of the tie 39 which is to be readzed, in those cases where the seat of the tie is to be reformed in accordance with a rail cross-section differing from the original rail cross-section.

70 Figs. 8 and 9 show two different forms of readzing devices.

The apparatus of Fig. 8 is mounted on pairs of 75 wheels or rollers 41 running over the service track and connected through the bar 42 carrying the two usual adzing tools 43, 43 controlled me-

chanically, pneumatically or electrically. The apparatus is capable of two adjustments. On one hand the tools are mounted on a common carriage 44 which may be moved as a whole along the bar 42 under the action of the handwheel 45. On the other hand the micrometric screw 46 controlled by the handwheel 47 allows the spacing between the two tools to be varied, an action which is necessary in view of the curves where the gauge is increased.

80 In the modification of Fig. 9 the pairs of wheels 41 are secured to the transverse bar 42 through the agency of jacks 48 which allow the horizontal position of the bar 42 to be restored. The screw 49, cooperating with the nut 51 carried by the connecting rod 52, provides means for the simultaneous displacement of the adzing tools 43-43.

85 The boring device shown in Fig. 10 comprises mechanical, pneumatic or electric boring tools 55 connected together through a cross-bar 56 provided with pairs of wheels 57 running over the service track 8.

90 Lastly Figs. 11 and 12 show a device which may be used for impregnating the new seats and bored holes with a preservative. This device 100 comprises pairs of wheels 58 adapted to run over the service track and held at the desired spacing or gauge by means of a rigid frame 59 carrying the preservative containers 61. The frame 59 carries a brush 62 adapted to remove wood 105 shavings and the like from the part of the sleeper which is to be treated with the preservative. This brush is secured to the front of the device, assuming motion in the direction of the arrow. On the other hand a spraying nozzle 63 is in communication with the reservoir 61 and the distance between the brush 61 and the nozzle 63 110 is equal to the spacing between two ties 39.

95 Of course these apparatuses have been described only by way of example and we may 115 execute the method according to our invention through the agency of any other automatic or nonautomatic devices.

100 The arrangement shown in Figs. 13 to 14 provides considerable facilities for sliding or moving the rails, this rail sliding or moving operation generally being rather toilsome. The arrangement illustrated comprises an elongated support 65 to the ends of which are secured, through the agency of nuts, two roller bearings 120 66 carrying a roller 67. Several of these supports are disposed on the ground at suitable points. The rail resting on these supports is very 125 easy to handle.

130 What we claim is:

1. A method for replacing railroad rails comprising laying the new rails to form service tracks, carrying rail removing and track preparing devices parallel to the track under replacement, removing the old rails from the track 135 under replacement with the rail removing device, preparing the said track for the new rails and shifting the new rails in place on the said track with the track preparing device.

2. A method for replacing railroad rails comprising laying the new rails to form service tracks, carrying rail removing and track preparing devices parallel to the track under replacement, removing the old rails from the track under replacement through the agency of the rail 145 removing device, laying them on cars running over the latter track ahead of the point of replacement through the agency of the same device, advancing the latter device for continuation of the removal of the old rails, and shifting 150

the new rails in place on the track under replacement.

3. A device for replacing railroad rails including travelling jacks which comprise pairs of wheels adapted to run over a service track the rails of which are on the outside of and parallel to the main track under replacement, jacks supported by these rails, a rigid bar carried by these jacks at an adjustable height over a flat car running on the main track, and rail holding and raising means adapted to run along said bar; a wheeled frame adapted to run over the main track and comprising an outer pair of wheels adapted to run over the wider service track, and means for modifying the vertical position of these outer wheels with reference to the frame; brushing means adapted to run over the service

track for brushing the ties of the main track, readzing means adapted to run on the service track and comprising two readzing tools adapted to move together transversely with reference to the track, and means for adjusting the spacing of said tools; a boring device adapted to run over the service track for boring holes in the ties and a preservative applying device adapted to run over the service track and comprising a container for a preservative solution, nozzles for spraying said solution on to the sleeper and brushes at the front of the nozzles for brushing the parts of the ties which are to be impregnated.
